(57) **CLAIM**

The ornamental design for a plush toy, as shown and described.

DESCRIPTION

FIG. 1 is a perspective view of the plush toy, showing the new design;

FIG. 2 is a front elevational view of the plush toy thereof;

FIG. 3 is a rear elevational view of the plush toy thereof;

FIG. 4 is a left side elevational view of the plush toy thereof;

FIG. 5 is a top plan view of the plush toy thereof; and,

FIG. 6 is a bottom plan view of the plush toy thereof.

A right side elevational view of the plush toy is a mirror image of the left side elevational view of the plush toy shown in FIG. 4.

1 Claim, 6 Drawing Sheets
